UNITED STATES PATENT OFFICE.

THOMAS J. KEAN, OF PHILADELPHIA, PENNSYLVANIA.

MEANS FOR ANALYTICALLY RECORDING GAIT OF HORSES.

SPECIFICATION forming part of Letters Patent No. 546,700, dated September 24, 1895.

Application filed December 5, 1894. Serial No. 530,862. (No model.)

To all whom it may concern:

Be it known that I, THOMAS J. KEAN, a citizen of the United States, residing in the city and county of Philadelphia and State of Pennsylvania, have invented certain new and useful Improvements in Means for Analytically Recording the Gait of a Horse, of which the following is a full, clear, and exact description, reference being had to the accompanying drawings, forming a part of this specification.

The object of this invention is to provide a novel and efficient means for analytically recording the gait—*i. e.*, the foot and leg motions—of a horse, to the end that any peculiar or faulty actions of the animal, together with the remedy therefor, may be accurately and expeditiously determined.

With this object in view the invention consists in the provision of novel electrically-controlled recording mechanism, and in the operative connection thereof with a contact device or devices suitably disposed on the shoe or shoes of the animal, whereby the periodical action of such device or devices upon the ground, in point of time and position, will effect the operation of said mechanism in such a manner as to be progressively and relatively recorded thereby.

The invention consists, also, in novel features of construction and organization, that will hereinafter be particularly described and claimed.

Referring to the annexed drawings, Figure 1 is a side elevation of the apparatus as in actual use, the side of the wagon being broken away for clearness. Fig. 2 is a plan, enlarged, of the electrically-controlled recording mechanism as mounted in the wagon. Fig. 3 is a side elevation of a means for throwing said mechanism into and out of operation. Fig. 4 is a partial longitudinal section, as on the line 4-4 of Fig. 2. Fig. 5 is a vertical section through the lower portion of a hoop, its shoe, and adjuncts. Fig. 6 is a full horizontal section, as on the line 6-6 of Fig. 5. Fig. 7 is a detail vertical section, as on the line 7-7 of Fig. 5. Fig. 8 is a diagram illustrating the several electrical connections between the respective shoes and the recording mechanism. Fig. 9 is a plan of a portion of the strip or web with the analysis recorded thereon.

Fig. 10 is a vertical section of a modified construction of recording apparatus, hereinafter referred to. Fig. 11 is a plan of a portion of said construction.

A designates an electrically-controlled recording apparatus suitably disposed within the wagon, which apparatus, in a convenient and efficient form, is of the following construction: *a* is a base-board, upon which is supported a series of electromagnets *a'*, the number of the series being determined by and corresponding with the number of contact devices (hereinafter described) in the shoes of the animal. In the present instance there are three contact devices in each shoe, and in consequence twelve magnets are provided. The armature *a²* of each of the magnets is connected with one end of a horizontal arm *a³*, the forward end of which is connected with a depending spring-plate *a⁴*. The several plates are arranged in sets of three, as seen in Fig. 2, corresponding with the number of contact devices on each shoe, the respective sets being disposed at slight intervals apart. (See Fig. 6.) The arms converge from the armatures to these plates, as seen in Fig. 2, and the relative arrangement of parts is such that if the electric circuits between the magnets, or any of them, and the batteries be alternately broken and completed the depending spring-plates will be oscillated. Clamped or otherwise secured to the free ends of the depending springs are pencils *a⁵* or other marking devices, which are adapted to impinge against a contiguous traveling strip *B*, of paper or the like, and to imprint thereon parallel lines or dashes indicating the duration of the completed circuit or circuits. The strip is moved at a given rate of speed in reference to that of the horse, so that the relative lengths and intervals of the dashes will accurately prescribe the condition of the respective contact-points on the shoes of the animal. The contact-points, by which the respective circuits are controlled, may be applied to the horse's hoofs in any suitable manner. In the construction illustrated herein there is interposed between each shoe *C* and the hoof a supplemental shoe *c*, of vulcanized rubber or other non-conductor, in which are disposed at predetermined points three plates

$c' c^2 c^3$ of conducting material, provided with binding-screws c^4 , respectively. (See Figs. 5, 6, and 7.) The interposed shoe c is preferably formed with a flange c^5 , which coacts with the inner edge of the shoe proper, so as to insure the proper disposition of the former, and it is also preferably made in sections, as seen, so that it may be used in connection with horseshoes of various sizes. The metallic shoe C is perforated at points in line with the plates $c' c^2 c^3$ on the interposed non-conducting shoe, and vertically-movable studs c^6 are fitted to the perforations thus formed. The upper ends of these studs are maintained normally depressed and out of contact with the respective plates by means of suitably-disposed springs c^7 , while their lower ends project below the metallic shoe. Hence by depressing these studs, or any of them, into contact with the plates an electric connection will be effected between the shoe and such plates or plate. In the present instance a separate battery D is provided for each magnet, the positive poles of the battery being connected with the respective plates by a wire d and the negative poles being connected by means of wires with a common return-wire d' , which is in its turn connected with the metal shoe. Thus there are three electric circuits, which are broken between the plates and their studs, respectively, and consequently if the contact be made between the shoe and any of the plates, as above stated, a circuit will be completed, the energized magnet thereupon effecting the operation of the connected pencil; or, in other words, should the horse whose gait is being analyzed strike the ground in the first instance with the toe of his shoe the forward stud will be moved upward to complete the circuit, the pencil thus imprinting a dash upon the paper proportionate to the dwell of the stud upon the ground, and should he then in this step press the shoe to the right or to the left the corresponding stud will be operated, and the time and the position of the movement relative to that first named will be likewise recorded on the strip; or should he strike the ground squarely with the shoe the three studs will be simultaneously operated, and such operation be transmitted to the recorder. Where, as in this instance, the four feet of the animal are equipped with the described devices, the respective movements of the feet in reference to each other will be recorded in parallel lines, the strides of the horse being indicated by the longitudinal spaces between the adjacent sets of dashes. Hence the gait of the horse will be accurately analyzed and recorded, and, as a result, any defective foot actions thereby appearing may be readily ascertained, to the end that proper curative measures therefor, such as the use of peculiarly-formed shoes, may be taken. The wires $d d'$ are extended along the legs of the horse, being held in place by means of suitably-disposed bands d^2 ; thence they are extended along the shafts of and into the

wagon, where they are connected to binding-posts d^3 on the base of the contained apparatus.

70

As a simple and efficient means whereby the strip of paper shall be fed to the markers at a prescribed rate of speed, in order that the relative lengths of the imprints in respect to the speed of the horse shall enable the active duration of the respective contacts to be accurately determined, I provide the following construction: E is a housing secured to the base-board and provided with a suitably-disposed bracket e , to which the upper ends of the depending spring-plates are fixed. (See Figs. 2 and 4.) In this housing, immediately in rear of the markers a^5 , carried by said plates, is rotatably mounted a feed-roller e' , the axis of which is preferably in line horizontally with the markers. In rear of this feed-roller are mounted two rollers $e^2 e^3$, one of which e^2 is a supply-roller, and the other of which e^3 is a take-up roller. The web or strip B is drawn from the supply-roller to and around the front of the feed-roller, thence to the take-up roller. Bearing upon the web or strip on the feed-roller is a smaller roller e^4 , the trunnions of which are supported in spring-actuated boxes e^5 in the housing, to the end that said roller e^4 will exert pressure upon the web on the feed-roller and keep it taut. On one of the trunnions or journals of the feed-roller is a pulley e^6 , which is belted with a similar pulley e^7 on the take-up roller. (See Fig. 2.) Hence when the feed-roller is properly rotated to draw the web from the supply-roller the take-up roller is simultaneously rotated in a manner to wind up the strip or web. On the journals of the supply-roller are tension-springs e^8 , which, coacting with the pressure-roller, insure the uniform contact of the traveling-strip with the feed-roller, and thus obviate the otherwise liability of the paper to buckle.

11

Although there is more than one way whereby the feed-roller may be impelled I shall describe a means which I consider very efficient and desirable. One of the trunnions of the feed-roller is extended beyond the housing and has connected therewith, by means of a universal joint f , one end of a stud f' , which is practically a continuation of said trunnion. On this stud is fixed a pinion f^2 , which is designed, by means below described, to be moved into and out of engagement with a pinion f^3 on the inner end of an adjacent stud f^4 . On the outer end of the latter stud is a sprocket-wheel f^5 , which is geared by means of a chain f^6 with a similar wheel f^7 on one of the carrying-wheels of the wagon, whereby during the traverse of the latter the motion will be transmitted from the carrying-wheel to the stud f' and its pinion. Hence if the pinion f^2 be engaged with the pinion f^3 the motion will be communicated to the feed-roller.

12

Fitted to suitably-arranged guide-brackets g on the base-plate is a longitudinally-mov-

13

able rod g' , one end of which is connected with a collar g^2 on the end of the pivoted stud by means of a link g^3 , and the other end of which is similarly connected with a normally-raised treadle G on the bottom of the wagon by means of a link g^4 , whereby the act of depressing said treadle will advance the pivoted stud and move its pinion into engagement with the pinion f^3 . The treadle is arranged

- 5 o near the front of the wagon, so that it will be convenient to the foot of the driver.

Hinged to the rear of the base-board is a transverse bar d^4 , on the upper face of which is arranged a series of contact-plates d^5 , which correspond with the poles of the respective batteries, the wires of the latter being connected with binding-posts on said contact-plates, respectively. (See Fig. 8.) These plates extend over the edge of the base-board

- 5 o and are adapted to be engaged with a corresponding series of contact-plates d^6 on the board, which latter plates are wired with the respective magnets and the contact devices on the shoes of the horse, whereby the entire
- 5 series of electrical connections may be simultaneously broken by properly turning the hinged contact-bar. The latter is normally maintained in the breaking condition by means of a bowed spring H , one end of which
- o is secured to the bar, while its free end bears upon the base-board. This bar is connected at one end by means of a spring s , chain h , slide h' , and link h^2 with the collar on the movable stud, whereby the spring H not only
- 5 acts to maintain the contact-bar out of action, but also the pinion on said stud. When the treadle is depressed by the driver, the contacts are first made along the bar, and immediately thereafter the feed-roller mechanism
- o is brought into operation. By this construction the operation of the machine is wholly under the control of the driver.

It is obvious that the condition of the contact-studs on the shoe may be reversed, so as normally to complete the circuits, in which case the contacts would be broken by their impact with the ground, and the markers be thereupon actuated. It is also obvious that the supplemental non-conducting shoe interposed between the main shoe and the hoof may be dispensed with, in which case the contact-plates would be embedded in the hoof. It is also obvious that instead of the recording mechanism above described other recording mechanisms may be used—as, for example, the construction illustrated in Figs. 10 and 11—namely, wherein the strip or web B is in the nature of a sensitized photographic film contained in a light tight box, said box 1 being provided with a row or series of transverse perforations 2, corresponding in number and position with the markers in the first-described arrangement, and being also provided with a series of slides or shutters 3, movable upon the perforations, which slides or shutters are formed on the ends of the arms a^3 , and are connected with the armatures a^2 of the

magnets a' in a manner to be reciprocated thereby similarly to the markers. It is evident that when the slides are opened periodically the light will act upon the adjacent surfaces of the moving film, so as to produce lines or dashes thereon proportionate to the duration of the exposure, and hence the time and the position of the respective contacts on the shoes of the horse will be photographically recorded.

I claim as my invention—

1. In means for analytically recording the gait of a horse the combination, with a receiving surface and means for advancing the same at a rate of speed controlled by that of the horse, of electrically-controlled means for automatically recording on said surface, circuit wires leading from said means to the hoof of a horse, and a contact device on said hoof connected with the circuit wires, substantially as described.

2. In means for analytically recording the gait of a horse the combination, with a strip or web, and means for feeding the same at a rate of speed controlled by that of the horse, of electrically controlled means for automatically recording on said strip, circuit wires leading from said means to the hoof of a horse, and a contact device on said hoof connected with the circuit wires, substantially as described.

3. In means for analytically recording the gait of a horse the combination, with an electrically-controlled recording device, of circuit wires leading therefrom to the hoof of a horse, and a series of independent contact devices on said hoof connected with the circuit wires, substantially as described.

4. In means for analytically recording the gait of a horse the combination, with an electrically-controlled recording device, of circuit wires leading therefrom to the respective hoofs of the horse, independent contact devices on said hoofs connected with the respective circuit wires, substantially as described.

5. The combination, with a strip or web, and means for actuating the same, of a series of markers adjacent thereto, magnets operatively connected with said markers, a battery or batteries, circuit wires connecting said battery or batteries with the magnets, and leading to the hoof of the horse, and a series of independent contact devices on said hoof connected with the circuit wires, substantially as described.

6. The combination, with a strip or web, and means for actuating the same, of markers arranged adjacent thereto in independent sets, magnets operatively connected with said markers, a battery or batteries, circuit wires connecting said battery or batteries with the magnets and leading to the respective hoofs of the horse, independent contact devices on said hoofs connected with the respective circuit wires, substantially as described.

7. The combination, with an electrically-controlled recording device, of circuit wires

leading therefrom to the hoof of a horse, a series of independent contact devices on said hoof connected with the circuit wires, and means for breaking the circuits simultaneously, substantially as described.

8. The combination, with a strip or web, and means for actuating the same, of a series of markers adjacent thereto, magnets operatively connected with said markers, a battery or batteries, circuit wires connecting said battery or batteries, with the magnets and leading to the hoof of a horse, a series of independent contact devices on said hoof connected with the circuit wires, means to break the electrical connections between the battery or batteries and the magnets, and means to throw the strip or web operating mechanism out of action, substantially as described.

9. In means for analytically recording the gait of a horse, the combination, with an electrically - controlled recording device, of a horse's shoe, a vertically-movable contact stud therein, a contact plate arranged adjacent to said stud and insulated from the shoe, and circuit wires connected with said plate, the shoe and the recording device, substantially as described.

10. In means for analytically recording the gait of a horse, the combination, with an electrically - controlled recording device, of a horse's shoe, a contact device therein, a supplemental shoe of non-conducting material provided with a contact plate, and circuit wires connected with said plate, the shoe and the recording device, substantially as described.

11. The combination, with a horse's shoe, of a series of contact devices arranged thereon, at predetermined points, a corresponding series of contact devices insulated from said shoe, and circuit wires connected with said latter devices and the shoe, substantially as described.

12. The combination, with a horse's shoe, and a series of contact devices arranged therein at predetermined points, of a supplemental shoe of non - conducting material provided with a corresponding series of contact devices, and circuit wires connected with said latter devices and the shoe, respectively, substantially as described.

13. The combination, with a horse's shoe,

and a series of contact devices arranged therein at predetermined points, of a sectional supplemental shoe of non-conducting material provided with a corresponding series of contact devices, and circuit wires connected with said latter devices and the shoe, respectively, substantially as described.

14. The combination, with a vehicle, of a mechanism therein comprising a suitable frame or housing, a web supply roller, a feed roller, and gearing between the feed roller and one of the wheels of the vehicle, electrically-controlled means for recording on the web, circuit wires leading from said means to the hoof of a horse, and a contact device on said hoof connected with the circuit wires, substantially as described.

15. The combination, with a vehicle, of a mechanism therein comprising a suitable frame or housing, a web supply roller, a feed roller, gearing between the feed roller and one of the wheels of the vehicle, and means for throwing said gearing into and out of operation, electrically-controlled means for recording on the web, circuit wires leading from said means to the hoof of a horse, and a contact device on said hoof connected with the circuit wires, substantially as described.

16. The combination, with a vehicle, of a mechanism therein comprising a suitable frame or housing, a web supply roller, a feed roller, gearing between the feed roller and one of the wheels of the vehicle, a series of markers adjacent to said feed roller, magnets operatively connected with said markers, a battery or batteries electrically connected with the magnets, a series of independent contact devices arranged on the hoof of a horse and connected with the electric circuits as described, means whereby the circuits may be simultaneously broken, and means whereby the feed roller gearing may be thrown out of operation, substantially as described.

In testimony whereof I have hereunto affixed my signature in the presence of two subscribing witnesses.
